ROLLER SKATE

Clarence Vogt, Wenonah, N. J.

Application May 22, 1936, Serial No. 81,325

11 Claims. (Cl. 280—11.26)

This invention relates to new and useful improvements in roller skates and more particularly to foot rests or plates therefor.

The principal object of the invention is to provide a device of the character set forth having a sectional foot rest or plate which is novelly constructed and arranged to eliminate a large number of parts, rivets and the like heretofore necessary in such structures.

10. Another object of the invention is to provide a foot rest or plate for devices of the present character which is of an extremely rugged, simple construction and relatively inexpensive to manufacture.

15. Another object of the invention is to provide a sectional footrest or plate for devices of the stated character the sections of which are adjustably connected together so that the skate may be adjusted to fit the various shoe sizes of different 20 skaters or allow for the growth and development of an individual owner or user thereof.

These and other objects of the invention and the features and details of construction thereof are set forth hereinafter and shown in the accompanying drawing, in which:

Fig. 1 is a view in side elevation of a roller skate embodying the present invention.

Fig. 2 is an inverted view in perspective of the front or toe section of the foot rest or plate of 30 the skate shown in Fig. 1.

Fig. 3 is a view similar to the disclosure in Fig. 2 of the rear or heel section of the foot rest or plate of the skate shown in Fig. 1.

Fig. 4 is a combined view in perspective of novel 35 means for adjustably securing together the front and rear sections of the foot plate shown in Figs. 2 and 3 respectively.

Fig. 5 is a view in section on line 5—5, Fig. 1; and

40 Fig. 6 is a view in section on line 6—6, Fig. 1.

Referring now more particularly to the drawing, reference numeral 1 designates generally the foot rest or plate of a roller or other skate made in accordance with this invention and comprising 45 front toe and rear heel supporting sections 2 and 3 respectively which are adjustably secured together in the manner hereinafter set forth.

In the present instance the front or toe section 2 of the plate 1 is stamped, pressed, or otherwise formed from a single blank of sheet metal material and includes a substantially flat foot supporting portion 4 having a double fold or rib 5 of metal 5 formed axially and perpendicular at the under side of said flat portion 4 with respect to the normal position thereof when in use. As shown, the fold or rib 5 is substantially co-extensive 50 in thickness and height with the fold or rib 5 of the flat supporting portion 4 of the front or toe section 2 so that said rib 5 may slide longitudinally or axially in the slightly wider space 7 between the parallel channel portions 6 of said front section 2 in the manner of a telescope with 55

use, said fold or rib of metal 5 and said flat supporting portion 4 terminating at their rear or inner ends in a pair of downwardly opening relatively spaced parallel channel portions 6 of substantial length having their upper or top surfaces disposed in a common plane parallel to and offset slightly below the plane of the upper surface of the flat supporting portion 4. As shown, the space 7 between the parallel channel portions 6 is arranged substantially co-axial with the fold 10 or rib 5 and the width of the former is slightly in excess of the thickness or width of the latter, thus disposing said channel portions 6 parallel to and at opposite sides of the longitudinal axis 15 of the section 2 of the foot rest 1.

In addition to the foregoing, pairs of relatively spaced lugs 8 including substantially vertical portions 9 and angularly offset portions 10 are pressed, stamped or otherwise formed at opposite sides of the flat supporting portion 4 of the section 2 adjacent the forward end thereof, said angularly offset portions 10 of said lugs 8 extending toward each other in a common plane substantially parallel to the plane of said flat supporting portion 4 and arranged to slidably support the usual shoe cleat elements 11. In the present instance, the cleat elements 11 are provided at their inner ends with downwardly extending flange portions 12 having threaded apertures or openings 13 formed therein for engagement with reversely threaded portions respectively of an adjusting screw or the like 14 which is rotatably mounted in a groove or slot 15 formed in the previously mentioned fold or rib 5 at the under side of the flat supporting portion 4 of the section 2, said reversely threaded screw or the like 14 being retained in slot 15 solely by said cleats 11 which in turn are retained in cooperative association with said flat supporting portion 4 by means of the lugs 8. 40

In a similar manner the rear or heel section 3 of the foot plate 1 is stamped, pressed, or otherwise formed from a single blank of sheet metal material and includes a substantially flat foot supporting portion 16 having a double fold or rib 17 of metal 17 formed axially and perpendicular at the under side of said flat portion 16 with respect to the normal position thereof when in use. As shown, the fold or rib 17 is substantially co-extensive 45 in thickness and height with the fold or rib 5 of the flat supporting portion 4 of the front or toe section 2 so that said rib 17 may slide longitudinally or axially in the slightly wider space 7 between the parallel channel portions 6 of said front section 2 in the manner of a telescope with 50

55

the portions of the surface at the under side of the flat supporting portion 16 of the section 3 at opposite sides of the fold or rib 17 thereof contacting or engaging the upper or top surfaces of said 5 channel portions 6 of the other or front section 2.

In addition to the foregoing, lugs or brackets 18 extend upwardly substantially at right angles from the flat supporting portion 16 of the rear or heel section 3 at opposite side edges thereof, 10 and provided with slots or apertures 19 to receive the terminal ends of the customary ankle straps or the like (not shown). An inverted T-shaped slot or opening 20 is also formed in the fold or rib 17 of the rear section 3 adjacent the forward 15 or inner end thereof and a bolt, screw or like securing element 21 having a head 22 is mounted in said slot 20 and provided with a lug 23 for engagement with the surface of said fold or rib 17 adjacent the slot 20 to prevent or limit relative rotation of said securing means 21 with respect thereto. In the present instance, the inner adjacent side walls 24 of the spaced parallel channel portions 6 are of less height than the outer walls 25 thereof so that when the front and 25 rear sections 2 and 3 are telescoped together in the manner previously set forth, sufficient clearance will be provided for the head 22 of the screw or bolt 21 and permit the same to overlie the edges of said inner adjacent side walls 24 in the relation shown in Fig. 6 of the drawing, to maintain the upper or top plane surfaces of said channel portions 6 in contact with the portions of the under surface of the flat supporting portion 16 at opposite sides of the fold or rib 17 thereof. 30

35 For the purpose of securing the front and rear sections 2 and 3 of the foot rest or plate 1 together in the desired longitudinal relationship with respect to each other, a channel member 26 is provided and has inwardly extending flanges 40 27 at its downwardly open side for engagement with the parallel channel portions 6 of the section 2 in the manner shown in Fig. 6 of the drawing, said member 26 being further provided with an aperture or opening 28 in the upper side thereof 45 of through which project the screw, bolt or like securing means 21 to receive a nut or like means 29 which is threaded thereon and tightened in the customary manner.

In the present instance, the front wheel assembly 50 is constructed in substantial accordance with United States Letters Patent No. 2,021,035 issued to me on November 12, 1935, and is secured at the under side of the front or toe section 2 of the foot rest 1 by means of rivets or like securing means 30, for which apertures or holes 31 are formed in the flat supporting portion 4 of said section at opposite sides of the fold or rib 5 thereof.

While a specific embodiment of the structural features and details of the invention have been set forth and described, it is not intended that said invention shall be precisely limited thereto, but that changes and modifications in the details of construction thereof may be incorporated where 65 within the scope of the annexed claims.

I claim:

1. In a device of the character set forth, a foot support comprising front and rear sheet metal 70 sections each formed to include a substantially flat supporting portion having a rib extending axially at the under side thereof, one of said sections terminating at its inner end in portions of substantial length arranged at opposite sides 75 of the axis of the section in spaced parallel rela-

tion to receive the rib of the other section therebetween.

2. In a device of the character set forth, a foot support comprising front and rear sheet metal sections each formed to include a substantially flat supporting portion having a fold therein extending axially at the under side of said flat supporting portions perpendicularly thereof, one of said sections terminating at its inner end in downwardly opening channel portions of substantial length arranged at opposite sides of the axis of the section in spaced parallel relation to receive the fold of the other section therebetween. 5

3. In a device of the character set forth, a foot support comprising front and rear sheet metal 15 sections each formed to include a substantially flat supporting portion having a fold therein extending axially at the under side of said flat supporting portions perpendicularly thereof, one of said sections terminating at its inner end in downwardly opening channel portions of substantial 20 length arranged at opposite sides of the axis of the section in spaced parallel relation to telescopically receive the fold of the other section therebetween. 25

4. In a device of the character set forth, a foot support comprising front and rear sheet metal sections each formed to include a substantially flat supporting portion having a rib extending axially at the under side thereof, one of said sections terminating at its inner end in portions of substantial length arranged at opposite sides of the axis of the section in spaced parallel relation to receive the rib of the other section therebetween, and means for 30 securing said sections together in the desired longitudinal relation. 35

5. In a device of the character set forth, a foot support comprising front and rear sheet metal sections each formed to include a substantially flat supporting portion having a fold therein extending axially at the under side of said flat supporting portions perpendicularly thereof, one of said sections terminating at its inner end in downwardly opening channel portions of substantial length arranged at opposite sides of the axis of the section in spaced parallel relation to receive the fold of the other section therebetween, and means for securing said sections together in the desired longitudinal relation. 40 45

6. In a device of the character set forth, a foot support comprising front and rear sheet metal sections each formed to include a substantially flat supporting portion having a fold therein extending axially at the under side of said flat supporting portions perpendicularly thereof, one of said sections terminating at its inner end in downwardly opening channel portions of substantial length arranged at opposite sides of the axis of the section in spaced parallel relation to telescopically receive the fold of the other section therebetween, and means for securing said sections together in the desired longitudinal relation. 55 60

7. In a device of the character described, a foot support comprising front and rear sections, one of which includes a substantially flat supporting portion having an axially extending rib at the underside thereof and the other of said sections including a flat supporting portion terminating at its inner end in channel portions of substantial length arranged at opposite sides of the axis of the section in relatively spaced parallel re- 70 75 75

lation to slidably receive the rib of the first mentioned section.

8. In a device of the character described, a foot support comprising front and rear sections, one of which includes a substantially flat supporting portion having an axially extending rib at the underside thereof and the other of said sections including a flat supporting portion terminating at its inner end in channel portions of substantial length arranged at opposite sides of the axis of the section in relatively spaced parallel relation to slidably receive the rib of the first mentioned section, and means for securing said sections together in the desired longitudinal relation.

9. In a device of the character set forth, a foot support comprising front and rear sheet metal sections each formed to include a substantially flat supporting portion having a fold therein extending axially at the under side of said flat supporting portions perpendicularly thereof, one of said sections terminating at its inner end in downwardly opening channel portions of substantial length arranged parallel to the axis of the section at opposite sides thereof in spaced relation to each other to receive the fold of the other section therebetween, a member engaging said channels and overlying the fold of said other section, means mounted in said rib of the other section and projecting through an opening in said member, said means overlying

the inner adjacent edges of said channel portions to hold the same firmly against the underside of the supporting portion of said other section, and means engaging the projecting portion of said last mentioned means to secure the front and rear sections of said foot rest together in the desired longitudinal relation.

10. In a device of the character set forth, a foot support comprising front and rear sections, one of which is formed to include a substantially flat supporting portion having a rib extending axially at the under side of said flat supporting portion, and the other of said sections having a flat supporting portion terminating at its inner end in portions of substantial length arranged parallel to the axis of the section at opposite ends thereof in spaced relation to each other to receive the rib of the other section therebetween, a member engaging said portions and overlying the rib of said other section, and means mounted in said rib of the other section and projecting through an opening in said member, said means overlying the edges of said portions to hold the same firmly against the underside of the supporting portion of said other section.

11. A device as claimed in claim 1, wherein the fold of the front foot supporting section is provided with a slot adapted to rotatably receive a screw.

CLARENCE VOGT.
